UNITED STATES PATENT OFFICE.

GEORGE MACHLET, JR., OF ELIZABETH, NEW JERSEY.

ELECTRIC REGULATOR.

1,227,921.

Specification of Letters Patent. Patented May 29, 1917.

Application filed July 1, 1912. Serial No. 706,951.

To all whom it may concern:

Be it known that I, GEORGE MACHLET, Jr., a citizen of the United States, residing in Elizabeth, in the county of Union and State 5 of New Jersey, have invented certain new and useful Improvements in Electric Regulators, of which the following is a specification.

This invention is an illustration of one

10 form of mechanism covered by certain claims in my co-pending application No. 464,140, filed November 23, 1908, (Patent No. 1,083,816, dated July 30, 1912), in which is disclosed a voltmeter and a regulating device which is dependent upon the position 15 of the needle of the voltmeter for regulating the condition of a work-apparatus.

In the present case there is illustrated an electrically heated furnace; and the invention 20 relates largely to means for controlling electrical currents, whether employed for heating a furnace or other purposes. Certain of the features of the present improvements are however, applicable also to regulators for fuel burning furnaces, and to many 25 other kinds of work-apparatus, whether electrical or of other kinds.

In said patent, there is shown a prime mover to operate the regulating device under 30 the control of the needle of the voltmeter or other indicating apparatus. A tactor is caused to beat repeatedly into and out of the path of the needle; but upon the tactor being arrested by engagement with the needle, a 35 shifting or adjustment is effected of the regulating device; while concurrently there is called into operation a companion tactor, which operates to shift the regulating device in the opposite direction as soon as the voltmeter needle has receded a little; either tactor being silenced while the other is active.

According to one feature of the present 40 improvements, the regulating device is in the form of a rheostat, which is connected in 45 an electrical main running to an electrical furnace, so that the heat of the furnace may be regulated. This rheostat has a movable arm or contact, which is given a step-by-step movement by the prime-moving member of 50 the improved regulator, so as to either throw in or take out resistance, and thereby reduce or increase the heat of the furnace, according to the position of the needle of the voltmeter. In some cases the electrical main 55 may itself be coiled around the magnet of the voltmeter, so as to affect the needle,

whereby the current in said main will be rendered self-regulative.

The movable arm of the rheostat is connected to a ratchet which is operated in 60 either one direction or the other by means of a double pawl which is connected directly to a prime-mover. This pawl is normally held by a spring out of engagement with the ratchet.

There is also employed a tumbler which is connected to said prime-mover to be reciprocated thereby, but which, under ordinary conditions, is arrested prematurely in each stroke, so that its movements are usually 70 idle; said tumbler having a yielding connection to the prime mover, to permit the latter to complete its operation independently of the tumbler. Whenever either

75 tactor is arrested by contact with the voltmeter needle, the tumbler is permitted to complete its stroke in one direction, and during such completion of the stroke, the tumbler forces the pawl into engagement with the ratchet, so that the latter is given a 80 movement, whereby the rheostat arm is turned or adjusted. During succeeding movements of the prime-mover, the pawl acts repeatedly, giving the ratchet wheel and the rheostat step-by-step movements. 85

This adjustment of the rheostat can occur in either direction, according to which of the tactors is active at the time. At the conclusion of the travel of the rheostat members in either direction, the active tactor is latched 90 out of use, and the other tactor is caused to become active, while all the strokes of the tumbler are again prematurely arrested, so that the travel of the rheostat arm ceases. In other words connection is continued until 95 the rheostat arm is swung to the limit of its travel, whereupon disconnection is automatically effected between the rheostat and the prime mover.

The prime mover may comprise a rotary 100 electrical or other motor, and in the present instance this motor is shown as geared to a reciprocating head, which has connections directly to said tumbler and to said rheostat-adjusting pawl. The prime mover may, 105 however, be used in connection with other forms of regulating devices, and the same is true of the tumbler mechanism, and of the pawl-and-ratchet mechanism herein disclosed.

110 Other features and advantages will hereinafter appear.

In the accompanying drawings,

Figure 1 is a diagrammatic perspective view, showing the present improvements in one form.

5 Fig. 1^a is a diagram of a modification, showing the electric main connected with the voltmeter which governs the current flowing through the main so that the current may be directly self-governing.

10 Fig. 2 is a sectional elevation, illustrating the manner in which the tumbler connects to the ratchet wheel the pawl which is operated by the prime mover, whereby the ratchet wheel and rheostat may be adjusted or given a movement of one step at 15 the ensuing stroke of the prime mover.

Fig. 3 is a part sectional elevation of the invention, showing the reciprocating prime-moving head as about midway of its down 20 stroke after the ratchet wheel has been given a movement of one step in clockwise direction from its normal position; the shifter being shown in its midway position.

Fig. 4 is a view similar to Fig. 3, but 25 showing the method by which a pawl is brought into action to move the ratchet wheel in clockwise direction; the parts being shown at the completion of the down stroke from the Fig. 3 position.

30 Fig. 5 is a plan of the invention.

Fig. 6 is a sectional elevation of the tactor mechanism and tumbler, voltmeter and furnace.

Fig. 7 is a perspective view of the parts 35 seen at Fig. 6.

Figs. 8 to 11 are diagrammatic end elevations of the tactors and moving needle; Fig. 8 showing the needle midway between the tactors, thus permitting motion of both 40 of them at the operation of the tumbler; Fig. 9 showing one tactor latched up out of the path of the needle while the other tactor is beating down into said path; Fig. 10 showing the needle as arresting the lower 45 tactor of Fig. 9; and Fig. 11 showing the same tactor as latched up out of use while the other tactor is beating down into the path of the needle.

Fig. 12 shows the pawl being idly moved 50 at the down stroke of the tumbler and prime mover; the tactor which is not shown in this figure being latched up out of use, as at Fig. 8, and the ratchet wheel being shown as having made a revolution; the 55 shifter being in one of its extreme positions.

Fig. 13, like Fig. 12 shows the shifter in one extreme position, but it shows the tactor in the other extreme position, at the conclusion of the upstroke of the prime mover.

50 Fig. 14 illustrates the manner in which the switch is turned to a midway idle position at the beginning of the operation of adjusting the rheostat.

Fig. 15 shows the switch as turned to the 5 opposite extreme position from Fig. 12,

whereby the first tactor is silenced, and the other tactor is brought into operation. At this figure, the prime mover is understood as being at the bottom of its stroke.

Fig. 16 is a view similar to Fig. 12, but 70 showing the other tactor and sear instead of the tactor and sear seen at Fig. 12.

Fig. 17 is a view similar to Fig. 12, but 75 showing the beginning of the return movement of part 48^a.

Fig. 18 shows the parts in the same positions as at Fig. 14, and illustrates the other tactor and sear in place of those seen at Fig. 14.

Fig. 19 shows the pawl as shifted into 80 engagement with the ratchet wheel, to adjust the rheostat in the opposite direction from that illustrated at Fig. 14.

Fig. 20 illustrates the shifter as having been turned back to a midway idle position 85 as at Fig. 14.

Fig. 21 is a diagram to indicate the positions of the needle and tactor teeth when the parts are approximately in the Fig. 16 position, that is, to show where the needle is 90 at this time; Fig. 22 similarly corresponds with Fig. 17; Fig. 23 with Fig. 18; and Figs. 24 and 25 with Figs. 19 and 20.

The invention is herein shown as applied 95 to means for regulating an electrical current. For convenience, there is herein illustrated an electrical furnace which is heated by the regulated current of electricity. It will be understood that the invention or certain features thereof may be used for 100 regulating electrical currents for other purposes. It will also be observed that certain features of the regulating device may be used for effecting other regulation than that of electrical currents.

105 There is shown diagrammatically an electrical furnace 1 to which lead the electric mains 2. In the furnace is inserted an element 3 from which lead wires 4 and 5 to a voltmeter or other galvanometer 6, said wires being connected to a pivoted rotating coil 7, to which is attached, in the ordinary manner, a needle or indicator 8, which moves along a scale 9 to show the condition or heat of the furnace.

A lever 10 is caused by a prime mover to vibrate up and down, to cause a tooth or projection 11 on its free end to dip into and out of the path of the moving needle 8, and is intended to coöperate with said needle 11 at the proper time to reduce or cut off the current in the mains 2, to reduce the heat of the furnace. The tooth 11 is intended to be intercepted by the needle, whereby the lever or tactor 10 is arrested, and the desired 120 regulation of the main current is effected.

The tactor 10 is caused to beat by means of an electric or other motor or prime mover 12, a reciprocating slide 13, a tumbler 14 and a sear 15. The motor 12 may be con- 125

5 nected by pinion 16 and gear 17 to shaft 18, and on the latter may be provided a disk 19 having a wrist 20, Fig. 3, provided with a block 21 to slide in a groove 22 provided in a cross head 23 fixed upon the lower end of slide 13, whereby the latter is driven up and down with moderate speed at the operation of the motor 12. At its top the slide carries a head 24 to which is pivoted at 25 a yielding link or connection 26, the lower end of which engages a wrist 27 provided upon said tumbler 14, whereby the latter may be rocked to and fro. The tumbler is pivoted upon a stud 28 projecting from the framework of the machine.

20 A spring 29 tends constantly to dip the tacter 10 into the path of the needle; but such movement is controlled by the tumbler 14. The spring, it will be seen, is attached to the tacter 10, Fig. 3. The connection between the tacter 10 and the sear 15 comprises an arm 30 formed on or rigid with said sear 15 and having a universal joint or connection 31 with an arm 32, formed on 25 the tacter 10. The provision of the universal joint permits the adjustment of the tacter along the scale 9, as will presently appear. The tacter member is pivoted between its ends at 33 upon a support 34 in the volt-30 meter box 6.

35 As the tumbler 14 is turned toward the right or clockwise at Fig. 3 by the upwardly moving connection 26, a finger 35 on the sear rides down an inclined edge 36 formed on the lower side of an opening in the tumbler, and reaches the position seen at Fig. 13; the tacter 10 or its tooth 11 having, during this movement, dipped idly into the path of the voltmeter needle 8.

40 The link or connection 26 tends to raise or turn the tumbler 14 farther in the same direction during the completion of the up stroke of the reciprocating slide 13; but the tumbler or rocker 14 is arrested by the engagement of said sear finger 35 with a stop 35^a forming the end of the notch in the tumbler 14; and hence is given only a limited idle stroke; said slide 13 completing its up stroke independently of the tumbler 14.

45 To permit this independent movement of the slide, the link or connection 26 is preferably made in the form of a hook, having an open notch 37 to engage the wrist 27; a strong spring (connected at one end to the head 24 and at the other end to the link or hook 26) holding the notch firmly against the wrist 27, so that it is sure to drive the tumbler 14, while permitting the link or hook to yield when necessary during the final portion of any stroke of the slide 13. The position of the hook at the completion of the up stroke is seen at Fig. 13, in which it will be seen that the notch has passed up beyond the wrist 27.

50 Upon the down stroke of the slide 13, the

tumbler 14 remains stationary until the hook again catches upon the wrist 27 and swings the rocker downwardly or toward the left. During this movement, the finger 35 rides upon a cam edge 39 formed in said opening 70 in the rocker, which thereby vibrates the sear 15 and the tacter 10, to lift the tooth 11 above the needle 8 as at Fig. 12.

55 The movement of the tumbler 14 in this direction is limited by a pin 40 thereon, which engages an arm 41 which originally is in the path of said pin 40, Fig. 12. This arm is shiftable out of the path of the pin 40, to permit additional movement of the tumbler 14, as will presently be explained.

60 During the remainder of the down stroke of the slide 13, the link or hook 26 descends idly, an inclined edge 42 of the notch therein riding upon the wrist 27. Upon the succeeding upstroke of the reciprocating slide 85 13, the same moves idly until the notch in the hook 26 catches upon the wrist 27, to drive the rocker or tumbler 14 toward the right until arrested by the finger 35 of the sear 15; and these motions are repeated idly, 90 the tacter 10 or its tooth 11 dipping into and out of the path of the needle, until, owing to the heating up of the furnace 1, the needle 8 reaches a position beneath the tooth 11 on said tacter 10, as seen at Fig. 14.

95 The needle 8, of course, is yielding, and is carried down by the descending tooth 11 until it rests upon the edges of the groove 43 in the voltmeter into which the tacter dips. The tacter is hence arrested, and in consequence, the finger of sear 35 cannot dip into the depression 39 of the tumbler 14, and hence cannot catch upon the stop or shoulder 35^a, and cannot arrest the tumbler 14, which accordingly is swung up to the extreme limit of its stroke.

100 There is brought into play during this additional or final portion of the stroke of the rocker 14, a cam or other shifter 44 to swing toward the right a pawl 45, which is pivoted at its upper end at 46 to the rising and falling head 24, and is normally held by a spring 47 away from pins or teeth 48 forming a ratchet wheel 48^a, which is fixed upon a shaft 49, upon which is also fixed the rotary member 50 of a rheostat 51, which is in circuit with the mains 2 leading to the furnace 1, whereby the current in said mains may be regulated, and the heat of the furnace correspondingly raised or lowered.

110 The pins 48 are at intervals agreeing with those at which are placed contacts 52 upon the rheostat, so that when the ratchet wheel 48^a is moved a distance of one tooth thereon, the member 50 of the rheostat will be shifted from one contact to the next, thus introducing either more or less resistance into the power circuit.

115 Said cam or shifter 44, which is rigid with the rocker 14, thrusts the pawl 45 to 120

the right, so that a tooth 53 thereon, Fig. 2, engages one of the pins 48 of the ratchet wheel 48^a in preparation for rotating said ratchet counterclockwise at Fig. 2, during 5 the ensuing downstroke of the primary slide 13.

During the next stroke of the slide 13, therefore, the ratchet wheel 48^a and the rheostat contact 50 are driven counterclockwise at Figs. 1 and 2 to an extent equal to 10 the interval between two teeth on the ratchet wheel, or say one-sixth of a revolution, so that the revolving contact 50 is shifted to the next contact 52, thereby throwing more 15 resistance into the power circuit 2, and reducing the heat of the furnace, or at least checking the increase of the heat thereof.

It will be understood that as the tumbler 14 continues to rock up and down, the tooth 20 11 intermittently releases the needle 8 to permit the latter to retrace its movement in case the furnace cools. To secure the releasing 25 of the needle, the point or upper end of the cam edge 36 is made higher than the stop 35^a, that is, closer to the pivot 28 of the tumbler 14, so that while the finger 35^a of the sear may escape said stop, so as to permit full upward movement of the rocker, it is still possible to be engaged by the cam 30 edge 39 during the downstroke of the rocker, whereby the tooth 11 is lifted and the needle 8 is released.

In order to maintain the heat of the furnace at the desired point, a second beater or tacter 54 is provided, having a tooth 55 to engage the needle, and having an arm 56 connected by a universal joint 57 to an arm 58 provided upon a sear 59 which has a finger or tooth 60 to fall into a notch on the upper edge of the rocker 14, one edge of said 40 notch constituting a stop 61, and the other edge 62 of said notch forming a cam to raise the sear and the tacter 54 in opposition to the tension of its spring 63.

45 It will be understood that while the needle is under the tooth 11 of one tacter, the other tacter will beat repeatedly at the continued rocking of the tumbler 14, occasioned by the movements of the slide or prime regulator 13, 24. The sear 59, together with the tacter 54, may be maintained out of use by means of a shifter 64, as seen at Fig. 16, said shifter preferably being formed of the same piece of metal as the stop arm 41, and pivoted on a stud 65, fixed upon the machine frame.

During the first counterclockwise movement of the ratchet wheel 48^a, a tappet 66 on said ratchet wheel, which originally occupies the position seen at Fig. 19, engages an arm 67 formed upon said members 41, 64, and thereby swings 64 down to permit the sear 59 to perform its vibrations. It is noted that at the same time the stop arm 41

is swung to a position of disuse (see Fig. 65 14), so that it can no longer arrest the rocker 14; but the latter is nevertheless arrested by means of the finger 60 on the sear 59, so that the counterclockwise stroke of the tumbler 14 is shortened, for a purpose which will 70 presently appear.

The members 41, 64, 67 at Fig. 14 are midway between their extreme positions, as will also presently appear; but the arm 64 is nevertheless far enough down at this time to 75 permit the sear 59 to operate.

As so far described, the ratchet wheel 48^a and its associated rheostat contact 50 have taken only one step; but it will be understood that during the next cycle of movements of the tumbler 14, said ratchet wheel and rheostat contact will be given another stroke, and that the counterclockwise revolution of said members will continue step-by-step, each step throwing more resistance 85 into the main circuit 2, until said resistance reaches a maximum, or until the current is completely shut off. A revolution of the rheostat contact 50 through 300 degrees may effect an opening of the circuit 2, if desired. 90

It will be understood that the regulating device may be operated in connection with any desired rheostat or combined rheostat and circuit opener, or other electrical device. It will also be understood that the 95 ratchet wheel may be used for gradually closing and opening, or for gradually rotating in the opposite direction any other kind of regulator, whether used for regulating electricity, or for regulating the flow of air, 100 or fuel, or liquid, or for gradually effecting other purposes. Member 50 may be loose on shaft 49, and a fork 50^a fixed on the shaft may turn idly during the first step of wheel 48^a in either direction, and then engage the 105 member 50 to rotate it step-by-step through 300 degrees only.

If the heat of the furnace 1 does not diminish promptly, the needle 8 will remain under the tooth 11 of the first tacter (the 110 second tacter beating meanwhile) until after the ratchet wheel 48^a has made a complete counterclockwise revolution. During the last step of said revolution, the tappet 66 on said ratchet wheel engages an arm 68, 115 which may be integral with 41, 34, 67, and swings this shifter device from the midway position at Fig. 14 to the extreme position at Fig. 15.

In moving to the extreme position, a finger 120 69 on the arm 67 of the shifter takes under the sear 59, and lifts the same far enough not only to carry the tacter tooth 11, but a pendulum guard 70 entirely clear of the needle 8, thus permitting the needle to move past the tacter 10, in case the heat of the furnace should continue to increase before the reduction in the current in the electric mains takes

effect upon the furnace. At the same time, the stop arm 41 is swung up into the path of a pin 71 projecting from the upper part of the tumbler 14, so as to limit the movement of said tumbler in clockwise direction through the continued reciprocations of the primary member 13, 24. The movement of said tumbler is therefore limited in one direction by the stop arm 41, and in the opposite direction by the finger or tooth 60 on the sear 59; the hook 26 yielding at both the top and bottom of the stroke to permit the member 13 to finish its stroke in each direction.

15 It will be understood that the shifter 44 can no longer reach the pawl 45, and hence the latter cannot be thrown into engagement with any of the pins of the ratchet wheel 48^a, so that the latter ceases to rotate, 20 and the rheostat member 50 remains in engagement with the contact 71 which is connected to the greatest resistance, or which may be a mere insulating device, so that the main circuit is broken.

25 The primary member 13, 24, and the tumbler 14 will now move up and down idly, and the tactor 54 will dip idly into the path of the needle 8, until by reason of the cooling of the furnace, the latter swings back far 30 enough to intercept the tooth on the tactor 54, whereby the same is arrested, so that the tooth 60 on the sear 59 cannot descend far enough to engage the stop 61 on the tumbler 14, thus permitting the hook 26 to swing 35 said tumbler downwardly or counterclockwise, to its extreme position, Fig. 19.

At this time, a shifter 73 fixed on said tumbler 14, engages the hook 45 (the latter being at the bottom of its stroke) and pushes 40 the latter into engagement with one of the teeth or pins 48 of the ratchet wheel, as at Fig. 4; said pawl having a lower tooth 74 to engage beneath the pins or teeth 48, to lift the same and rotate the ratchet wheel 45 48^a toward the right or clockwise, during the ensuing up stroke of the primary member 13, 24. The ratchet wheel 48^a and the rheostat member 50 are accordingly turned through one-sixth of a revolution, and the 50 tappet 66 on said wheel engages an arm 81 of the shifter device, to rock said shifter to a midway position (see Fig. 3). The switch device may be held frictionally in any of its rotative positions, either by making it 55 fit tightly in its bearings, or by other suitable means; and the same is true of wheel 48^a and of the rheostat arm 50.

The movement of the shifter to a midway position withdraws the arm 87 thereon sufficiently to permit the sear 15 to resume its activity, whereby the tactor 10 is again caused to beat, and whereby the movement of the tumbler 14 in clockwise direction is arrested, so that the hook 45 cannot be swung

into engagement with the ratchet wheel, 65 when said hook is in its uppermost position, and hence the hook can only act to turn the ratchet wheel 48^a in clockwise direction.

At the completion of each downstroke, the shifter 73 reconnects the lower tooth 74 of 70 the hook with one of the teeth of the ratchet wheel, so that the latter is intermittently rotated; thus operating through the rheostat to gradually reduce the resistance in the electric mains, and thereby to increase the heat 75 of the furnace.

If the needle 8, however, does not promptly respond, the operation of turning the wheel 48^a and the rheostat clockwise will continue until the same reach their initial 80 positions; the tappet 66 finally engaging the arm 88 and swinging the shifter device from its midway position at Fig. 3 to its extreme position at Fig. 12, whereupon arms 64 raise the sear 59 sufficiently to lift the tactor 54 85 to the extreme position at Fig. 19, lifting not only the tooth 55, but a pendent guard 70 thereon, out of the path of the needle 8. At the same time, stop arm 41 is brought into position to coöperate with the pin 40 to 90 limit the stroke of the tumbler 14. Neither of the shifters 44, 73 can now swing the hook 45, and hence the latter rides up and down idly, its spring 47 pressing it lightly against the hub of the tumbler 14. 95

Since the heat of the furnace increases, the needle 8 moves forward again, and the cycle of operations is repeated. It will be seen that the connections and operations of the tactors 10 and 54 are substantially the same. 100

The needle 8 of the voltmeter thus moves from zero position up to the field of the duplex tactor mechanism, and then has slight oscillation in said field from one tactor to the other, whereby the heat of the furnace 105 or the regulation of the electric current is maintained within exceedingly close limits.

The support 34 for the tactor levers is in the form of a lug cast upon a hollow or cup-like support 82 sunken below the cover 83 110 of the voltmeter box, and consisting of two parts 84 and 85, formed to catch over the top and bottom edges of a circular hole 86 formed in said cover, said part 85 fitting in said hole, and the latter being concentric to 115 the rotative axis of the needle 8. Said parts 84 and 85 are rigidly joined by screws 87 to form a hollow bushing, or a swiveled supporting head for the tactor levers. The universal joints of said levers with the sear 120 levers are in the bottom of the cup, in proximity to the axis of movement of the swiveled head, so that the head may be swung in either direction without disturbing the connection between the tactor levers and the 125 sear levers. The arms 30 and 58 of the sear levers are bowed, to carry them up out of the cup and down again to their fixed pivot 88.

Any desired adjustment of the tacter levers may be effected by turning a finger piece 89, provided upon the end of a horizontal shaft 90, journaled in bearings 91 on said cover, and having at its inner end a worm 92 in mesh with a segment of a worm wheel 93 formed upon the top cup member 84. By turning said finger piece 89, the tacter levers may be adjusted to any desired point on the usual voltmeter scale 9, thus providing for any required heat of the furnace or regulation of the main electrical current; and the needle will automatically move to said point, and the heat of the furnace will remain substantially at that point for an indefinite time.

The tacter lever arms 32, 56, extend through a small hole 94 in the wall of the lower member 85 of the cup.

Fig. 12 shows the clockwise limit of the wheel 48^a and the rheostat arm 50, at which position all of the resistance is out of the circuit. When the shifter is at the extreme position seen at Fig. 12, the tacter 10, 11, beats up and down idly, the same being shown in this figure as at the top of its stroke. It will be understood that the prime mover 13, 14 is now at the bottom of its stroke; the tumbler 14 having been arrested by engagement of its pin 40 with arm 41 of the shifter, and the link 26 having slipped past the stud 27, in completing its stroke after the arrest of the tumbler 14.

In Fig. 13, the position of the shifter 41 is the same, but the tacter is seen at the bottom of its stroke; the prime mover 24, 13 being understood to be at the top of its stroke, and the link 26 having again slipped past the stud 27 on the tumbler 14, to complete its upstroke; the tumbler being at this time arrested by the engagement of the finger 35 with the abrupt end 35^a of the notch in the tumbler. Hence while the shifter 41 is at the position seen in these two Figs. 12 and 13, the tacter 10 will continue to beat idly up and down. The other tacter (not shown in these two views) is latched up by the arm 64, as seen at Fig. 16, and as also indicated diagrammatically at Fig. 9.

When the needle 8 travels to the left from the position at Fig. 9 to the position at Fig. 10, it intercepts the tooth 11 and arrests the tacter 10 in such position that the sear tooth 35 can clear the stop 35^a on the tumbler 14, and hence the latter is enabled to complete its motion in clockwise direction, so that the shifter 44 can swing the pawl 74 into engagement with a tooth 48 of the ratchet wheel 48^a, to drive the same downwardly; the parts being seen at Fig. 14 as about midway of the down stroke of the prime mover 13, 24.

The pin 66 on the ratchet wheel engages the arm 67 of the shifter and swings the lat-

ter to its idle midway position at Fig. 14, the arm 64 simultaneously dropping or releasing the companion sear 59 (see Fig. 18), whereby the tacter tooth 55 is permitted to beat down into the path of the needle 8. In consequence, the finger 60 of the sear 59 is enabled to drop into the notch 62 and arrest the tumbler 14, so that the latter cannot complete its counterclockwise stroke, and hence the spring 47 (see Fig. 4) can at the conclusion of the downstroke (or beginning of the upstroke) of the prime mover, withdraw the pawl 74 from the ratchet wheel, and hold said pawl away from said ratchet wheel during the idle upstroke of the prime mover. From this, it will be understood that during successive reciprocations of the prime mover, the pawl 74 will impart successive step-by-step movements to the ratchet wheel 48^a; each time giving it a stroke of say one-sixth of a revolution in a counterclockwise direction.

At Fig. 10, the needle 8 is now shown as caught under the tacter tooth 11; but it will be understood that said tacter tooth 11 continues to beat up and down to a limited extent, releasing the needle 8 at every stroke, to permit the same to swing toward the tacter tooth 55, in case the heat of the furnace rapidly diminishes; and said needle may arrive at a position midway between the two teeth 11 and 55, in which event both tacters will beat up and down, either being ready to engage the needle. If the withdrawal of the needle 8 from the tooth 11 thus occurs before the ratchet wheel and rheostat make a complete revolution, the tooth 35 will again be able to arrest the tumbler 14, so that the latter cannot make a full stroke in clockwise direction, and hence the pawl 74 will be wholly disabled, and the rheostat arm will maintain its last adjustment until there is further fluctuation in the heat of the furnace, whereupon the rheostat arm will be adjusted automatically in either one direction or the other, according to the character of the fluctuation in the furnace heat. It will be seen that both teeth of the pawl 74 are hooked, so as to hold the pawl in engagement with the ratchet teeth during a full stroke of the pawl in either direction.

Assuming, however, that the needle 8 remains under the tooth 11, as at Fig. 10, the pawl 74, by repeated strokes, revolves the ratchet wheel 48^a counterclockwise until it completes a full revolution to the position at Fig. 15, at which figure it will be seen that the pin or wrist 66 on the ratchet wheel has engaged the arm 68 of the shifter, and swung the latter to the extreme opposite position from Fig. 12, with its arm 64 elevated to engage the pin 71 on the tumbler, to limit the upstroke of said tumbler; while the arm 67 of said shifter has engaged the sear 15, and latched it up out of use. The pawl 74

tooth 11 of the associated tactor being held above the needle 8, as at Fig. 11, so as to permit the needle to swing beneath and beyond the guard 70 on said tooth, in case the heat 5 of the furnace continues to increase temporarily.

While the shifter is in the Fig. 15 position, the tactor 54 may continue to beat up and down idly between the positions seen at 10 Figs. 18 and 20; the arm 41, by engagement with the pin 71, limiting the stroke of the tumbler 14 in one direction, while the sear finger 60, by engagement with the shoulder 61 on the tumbler, limits the stroke of the 15 latter in the opposite direction.

This idle beating of the tactor 54 continues until the furnace cools sufficiently to cause the needle 8 to swing to the position at Fig. 24, whereby the tactor 54 is prevented from completing its downstroke, and hence the sear finger 60 is held up clear of the shoulder 61, and therefore the tumbler 14 is permitted to complete its downstroke, whereby the shifter 74, at the conclusion of 25 the downstroke of the prime mover 13, 24, swings the pawl 74 into engagement with a tooth of the ratchet wheel 48^a, to turn the same in clockwise direction during the ensuing upstroke of said prime mover 13, 24.

During this initial return movement of 30 the ratchet wheel 48^a, the pin 66 engages arm 81 on the shifter 41, and swings the said switch to the midway position illustrated at Fig. 14, whereby the finger 69 on 35 the shifter arm 67 is caused to release the sear 15, and hence the tactor 10, 11 is permitted to beat up and down, so that the needle 8 is intermittently released. The needle may then proceed to a position between the two tactors, whereupon both will 40 make full up and down strokes, as already explained. If, however, the needle does not swing, the pawl 74 continues to work the ratchet wheel and rheostat arm around until 45 the pin 66 reaches the Fig. 12 position, thus completing the cycle of adjustments.

At Fig. 1^a the voltmeter is shown diagrammatically as connected with the electric main, and it will be understood that 50 the same tactor and prime moving mechanism is employed as in the other views, to control the current in said main.

Variations may be resorted to within the 55 scope of the invention, and portions of the improvements may be used without others.

Having thus described my invention, I claim:

1. The combination of a main electrical circuit, a current regulator in said circuit, 60 a work-apparatus operated by the current flowing through said circuit, a voltmeter having a movable needle, an independent circuit affected by said work-apparatus, said voltmeter included in said independent circuit, a member caused to dip repeatedly and

frequently into the path of said needle, means connected to said dipping member and rendered effective by the coöperation of said needle and said dipping member for adjusting said current regulator; said needle 70 being movable freely past said dipping member, and a scale to coöperate with said needle throughout its range of movement, to indicate the condition of the work-apparatus.

2. The combination of a main electrical circuit, a current regulator in said circuit, an electrical furnace in said circuit, a voltmeter having a movable needle or part, a voltmeter circuit having an element in said furnace, and means, inclusive of a member caused to dip repeatedly and frequently into the path of said needle, for adjusting said current regulator; said needle being movable freely past said dipping member.

3. The combination with an electrical heating apparatus, of a movable indicator to show the temperature of the apparatus, a prime mover, means connected therewith to dip repeatedly into the path of said indicator, a rheostat, and a step-by-step rheostat-operating mechanism set into repeated action by means of the engagement of said dipping part and said indicator, and having means to control the electrical current to said heating apparatus; said indicator movable past said dipping part.

4. The combination of a movable indicator, a tactor, a rheostat, a prime mover, means operable thereby and tending repeatedly to operate said rheostat, a sear controlled by said tactor and effective at the movement of the latter into the path of said indicator to prevent the operation of said rheostat, and means controlled by said rheostat to regulate an electric current which affects said indicator.

5. The combination of a movable indicator, a tactor, a ratchet, a prime mover, means operable thereby and tending repeatedly to operate said ratchet, a sear controlled by said tactor and effective at the movement of the latter into the path of said indicator to prevent the operation of said ratchet, and means controlled by said ratchet to regulate a work apparatus whose condition is shown by said indicator.

6. The combination of a rotating motor or driver, a regulating device, a connecting means between said motor and said regulating device, including a spring normally rendering said connecting means ineffective, a tumbler yieldingly connected to said motor, means controlled by the tumbler for rendering said connecting means effective, a voltmeter having a movable needle, a tactor caused by said tumbler to beat into and out of the path of the needle, said tactor being effective, when beating in the path of the needle, to arrest said tumbler and prevent

it from rendering said connecting means effective.

7. The combination of a driver or prime mover, a regulating device, a connecting means between said driver and said regulating device, including a spring normally rendering said connecting means ineffective, a tumbler, a yielding device operated by said driver to rock said tumbler to and fro, means controlled by the tumbler for rendering said connecting means effective, a voltmeter having a movable needle, a tactor caused by said tumbler to beat into and out of the path of the needle, said tactor, when beating in the path of the needle, being effective to arrest said tumbler and prevent it from rendering said connecting means effective.

8. The combination of a driver, a regulating device, a pawl and ratchet between said driver and said regulating device for operating the latter, a spring normally holding the pawl away from the ratchet, a tumbler, a yielding connection between said tumbler and said driver, said tumbler having means to move said pawl into engagement with the ratchet, a voltmeter having a movable needle, a tactor caused by said tumbler to beat into and out of the path of the needle, said tactor being effective, when beating in the path of the needle, to arrest said tumbler and prevent it from engaging said pawl with said ratchet.

9. The combination of a regulating device, a rocker having means to control said regulating device, a prime mover having a yielding connection to said rocker, a voltmeter having a movable needle, a tactor, a spring tending to move said tactor into the path of said needle, said rocker permitting the tactor to dip into the path of said needle, and means associated with said tactor and operative at such movement of the latter for arresting the rocker, and thereby rendering the prime mover ineffective to cause a complete operation of said rocker, so that the latter does not cause a movement of said regulating device.

10. The combination of a device having a movable needle or indicating part, a tactor movable into the path of the needle, a sear connected to said tactor, a tumbler engageable by said sear, a prime mover, a yielding device connecting said prime mover to said tumbler to reciprocate the same, said tumbler acting upon said sear to cause the tactor to dip into the path of the needle, and being also arrestable by said sear at such movement of the tumbler, and regulating means controllable by the tumbler at the final part of the stroke thereof effected by said yielding connection, when said sear is prevented from arresting said tumbler by reason of the engagement of the tactor with the needle.

65 11. The combination of a regulating de-

vice, a constantly revolving motor, a reciprocating member driven by said motor, a normally disconnected connecting means between said reciprocating member and said regulating device, a yielding device also operated by said reciprocating member and tending to connect said connecting means to said regulating device, a voltmeter having a movable needle, a tactor caused by said yielding device to beat into and out of the path of said needle, and means connected to said tactor and effective when the tactor dips into said path, to restrain said yielding device and prevent the full operation thereof, whereby when the tactor is arrested by contact with said needle, a full operation of the yielding device is effected by said reciprocating member, and the regulating device is consequently connected to said reciprocating member to be operated thereby.

12. The combination of a prime mover, a tumbler operable thereby, a movable needle or part, a tactor caused by said tumbler to beat into the path of said needle, said tactor having means to arrest said tumbler, and the tumbler being free to complete its movement when said tactor is arrested by the needle, a regulating device, means for enabling said tumbler to connect said regulating device to said prime mover to be actuated thereby, and means shifted by said regulating device to position to disable said tumbler from making said connection.

13. The combination of a prime mover, a tumbler having a yielding connection to said prime mover, an indicator having a movable needle or part, a tactor caused by said tumbler to beat into the path of said needle, said tactor having means to arrest said tumbler, and the tumbler being free to complete its movement when said tactor is arrested by the needle, a regulating device, means for enabling said tumbler to effect repeated connections between said regulating device and said prime mover, so that the regulating device is given a step-by-step movement, and means eventually operated by said regulating device to cause the tumbler to cease connecting the prime mover to the regulating device.

14. The combination of a prime mover, a tumbler having a yielding connection to said prime mover, an indicator having a movable needle or part, a tactor caused by said tumbler to beat into the path of said needle, said tactor having means to arrest said tumbler, and the tumbler being free to complete its movement when said tactor is arrested by the needle, a rotary regulating device, a normally idle pawl connected to said prime mover for operating said regulating device, means for enabling said tumbler to effect step-by-step operation of said regulating device by said pawl, and means eventually operated by said regulating de-

vice to cause the tumbler to cease connecting the pawl to the regulating device.

15. The combination of a prime mover, a tumbler having a yielding connection to said prime mover, an indicator having a movable needle or part, a tacter caused by said tumbler to beat into the path of said needle, said tacter having means to arrest said tumbler, and the tumbler being free to complete its movement when said tacter is arrested by the needle, a regulating device having a ratchet, a pawl connected to said prime mover for operating said ratchet, a spring normally holding said pawl away from said ratchet, and a shifter connected to said tumbler to engage said pawl, at the completion of the movement of the tumbler, and move said pawl into engagement with said ratchet.

20. 16. The combination of a prime mover, a tumbler having a yielding connection to said prime mover, an indicator having a movable needle or part, a tacter caused by said tumbler to beat into the path of said needle, said tacter having means to arrest said tumbler, and the tumbler being free to complete its movement when said tacter is arrested by the needle, a regulating device having a ratchet, a pawl connected to said prime mover for operating said ratchet, a spring normally holding said pawl away from said ratchet, a shifter connected to said tumbler to engage said pawl, at the completion of the movement of the tumbler, and move said pawl into engagement with said ratchet, and means connected to said ratchet for disabling the tumbler from shifting the pawl.

17. The combination of a prime mover, a tumbler, a yielding link extending from the prime mover to said tumbler to operate the latter, a voltmeter having a movable needle, a tacter caused by said tumbler to beat into and out of the path of the needle, said tacter having means to arrest said tumbler, the tumbler being free to complete its movement when the tacter is arrested by the needle, and a regulating device controlled by said tumbler during the completion of the movement of the latter.

18. The combination of a prime mover, a tumbler, a yielding link extending from the prime mover to said tumbler to operate the latter, said link having a notch, and one of said tumbler and prime mover elements having a wrist, a spring yieldingly holding said link notch in engagement with the wrist, a voltmeter having a movable needle, a tacter caused by said tumbler to beat into and out of the path of the needle, said tacter having means to arrest said tumbler, and the notch in said link being provided with an inclined edge, to permit the prime mover to complete its stroke after the tumbler is arrested by the tacter, the tumbler being

free to complete its movement when the tacter is arrested by the needle, and a regulating device controlled by said tumbler during the completion of the movement of the latter.

19. The combination with an electrical heating apparatus, of a movable indicator to show the temperature of the apparatus, a rheostat included in a circuit with said apparatus, a pawl and ratchet for operating said rheostat, said pawl normally ineffective, a prime mover having means to dip repeatedly into the path of said indicator, means controlled by the coöperation of said dipping part and said indicator, to cause said pawl to be operated by said prime mover to adjust said rheostat, and means for rendering the pawl ineffective at the conclusion of the adjustment of the rheostat.

20. The combination of a movable indicator, a pair of tacters, a ratchet, a prime mover tending repeatedly to operate said ratchet, a pair of sears connected to said tacters, one tacter to each sear, each sear being effective, at the movement of its tacter into the path of said indicator, to prevent the operation of said ratchet in one direction by said prime mover, a regulating device adjustable by said ratchet, and means to co-operate with said ratchet for rendering either one tacter or the other effective, and also to reverse the direction in which the prime mover can be effective upon said ratchet.

21. The combination of a movable needle, a prime-moving mechanism, two members, means for connecting said two members to said prime-moving mechanism so that either may be silenced while the other is caused to dip repeatedly into the path of said needle, a regulating device, and means rendered effective by the coöperation of said needle with said dipping members to effect operative connection between said prime-mover and said regulating device to adjust the same step-by-step in alternative directions, and to disconnect the regulating device from the prime-mover at the conclusion of the travel of the regulating device in either direction.

22. The combination of a prime mover, a regulating device, a normally disconnected connecting means from said prime mover to said regulating device, a tumbler, a device yieldingly connected to said prime mover and tending to render said connecting means effective, a movable indicator, tacters, either of which may be caused by said tumbler to beat into and out of the path of said indicator while the other tacter remains idle, means to enable the active tacter, only when dipping into the path of the indicator, to restrain such tumbler and prevent full operation thereof, whereby when the active tacter is arrested by contact with said indi-

cator, a full operation of the tumbler is effected by said prime mover, and the regulating device is consequently connected to said prime mover to be operated thereby, a 5 device having means to coöperate with either tacter to prevent effective strokes of said tumbler, and means controlled by the last-mentioned device to render either one tacter or the other effective, and to determine in 10 which direction said regulating device shall be adjusted by said prime mover.

23. The combination of a movable indicator, a pair of tactors, a ratchet, a prime mover tending repeatedly to operate said 15 ratchet, a pair of sears connected to said tactors, one tacter to each sear, each sear being effective, at the movement of its tacter into the path of said indicator to prevent the operation of said ratchet by said prime 20 mover, a regulating device adjustable by said ratchet, and means for enabling said ratchet to render either one tacter or the other effective, and also to reverse the direction in which the prime mover could be effective 25 upon said ratchet, and also to effect disconnection between the prime mover and the ratchet at the conclusion of the travel of the latter in either direction.

24. The combination of a main electrical 30 circuit, a current regulator in said circuit, an independent circuit, a voltmeter having a movable needle and a scale therefor and included in said independent circuit, a work device whose condition affects the current 35 flowing in said independent circuit, said work device included in said main circuit, a member caused to dip repeatedly into the path of said needle, means connected to said dipping member and jointly controlled by 40 said needle and said dipping member, for adjusting said current regulator; said needle movable past said dipping member; and means for adjusting the point in the path of 45 the needle at which it shall coöperate with said dipping member.

25. The combination of a minor electrical 50 circuit, a movable needle therein, a prime-moving mechanism, two members, means for connecting said two members to said prime- 55 moving mechanism so that either may be silenced while the other is caused to dip repeatedly into the path of said needle, a main electrical circuit, a regulating device there- 60 for, and means rendered effective by the co- operation of said needle with said dipping members, to effect operative connection between said prime-mover and said regulating device to adjust the same in alternative directions.

65 26. The combination of a main electrical circuit, a current regulator in said circuit, an electrically operated apparatus also included in said circuit, an independent electrical circuit having a part affected by the condition of said work apparatus, a voltmeter in said

independent circuit and having a movable needle or the like, means inclusive of a member caused to dip repeatedly and frequently into the path of said needle for adjusting said current regulator; said needle being 70 freely movable in opposite directions past said dipping member; and a scale for coöperation with said needle.

27. The combination of a main electrical circuit, a current regulator, a work-apparatus operated by the current flowing through said circuit, a voltmeter having a movable needle, an independent circuit affected by said work-apparatus, said voltmeter included in said independent circuit, a member caused 75 to dip repeatedly and frequently into the path of said needle, adjustable means for selectively varying the point in the path of the needle at which said dipping member shall operate, and means connected to said 80 dipping member and rendered effective by the coöperation of said needle and said dipping member, for adjusting said current regulator.

28. The combination of a main electrical 90 circuit, a current regulator, a work-apparatus operated by the current flowing through said circuit, a voltmeter having a movable needle, an independent circuit affected by said work-apparatus, said voltmeter included 95 in said independent circuit, a member caused to dip repeatedly and frequently into the path of said needle, adjustable means for selectively varying the point in the path of the needle at which said dipping member 100 shall operate, and means connected to said dipping member and rendered effective by the coöperation of said needle and said dipping member, for adjusting said current regulator; a scale being provided to coöperate 105 with said needle and with said adjustable means; and said needle being movable freely past said dipping member.

29. The combination of a current regulator, a voltmeter having a movable needle, 110 a member caused to dip repeatedly and frequently into the path of said needle, a mechanism settable into operation to adjust said regulator step by step, and means connected to said dipping member and rendered effective 115 by the engagement of said dipping member and needle, for setting said adjusting mechanism into operation to effect a series of step-by-step adjustments of said regulator.

30. The combination of a current regulator, a voltmeter having a movable needle, a member caused to dip repeatedly and frequently into the path of said needle, a mechanism settable into operation to adjust said 125 regulator step by step, and means connected to said dipping member and rendered effective by the engagement of said dipping member and needle, for setting said adjusting mechanism into operation to effect a se- 130

ries of step-by-step adjustments of said regulator; said needle being movable past said dipping member.

31. The combination with an electrical heating apparatus, of a movable indicator to show the temperature of the apparatus, a prime mover, means connected therewith to dip repeatedly into the path of said indicator, a rheostat, a step-by-step rheostat-operating mechanism set into repeated action by means of the engagement of said dip-

ping part and said indicator, and having means to control the electrical current to said heating apparatus; said indicator movable past said dipping part, a scale for said 15 indicator, and means for adjusting the point in the travel of the indicator at which said dipping part shall coöperate therewith.
